UNITED STATES PATENT OFFICE.

LEE DE FOREST, OF NEW YORK, N. Y., ASSIGNOR, BY MESNE ASSIGNMENTS, TO RADIO
TELEPHONE & TELEGRAPH COMPANY, A CORPORATION OF DELAWARE.

SIGNALING SYSTEM.

1,123,118.

Specification of Letters Patent. Patented Dec. 29, 1914.

Application filed July 8, 1907. Serial No. 382,675.

To all whom it may concern:

Be it known that I, LEE DE FOREST, a citizen of the United States, and a resident of New York, in the county of New York and State of New York, have invented a new and useful Improvement in Signaling Systems, of which the following is a specification.

My invention relates to signaling systems employing electromagnetic waves such for example as space telephone systems, and it relates more especially to transmitting systems in which an energizing circuit including a condenser and means for producing an electric arc, is employed to produce high frequency electrical oscillations.

The object of my invention is to improve the efficiency of such energizing circuit.

With this object in view my invention comprises a circuit including a condenser and arc electrodes, one of said electrodes being so constructed and arranged that by its consumption an atmosphere other than air is maintained about the arc.

Several embodiments of my invention are illustrated in diagram in the drawings which accompany and form a part of the present specification.

Figure 1 represents a space telephone transmitting system energized by a singing-arc circuit, one of the arc-electrodes of which is partly immersed in a suitable liquid and operates as a wick to draw said liquid up into the arc for creating the proper gas. Fig. 2 shows a modification in which one or both of the arc-electrodes is impregnated with inflammable material. Fig. 3 is another modification in which one of the arc-electrodes forms the wick of a candle of paraffin or other suitable material. Fig. 4 represents a further modification in which one of the arc-electrodes contains a core of inflammable material.

In the figures, G is a source of electrical energy herein shown as a direct current generator.

R is a resistance or impedance.

C is a condenser.

M is an oscillation transformer of which the primary is I_1 , and the secondary is I_2 .

A is a transmitting antenna.

E is an earth connection.

T is a transmitter, herein shown as a mi-

crophone transmitter, which may be located in the earth connector of said antenna. 55

The circuit, which includes the condenser C, the inductance I, and the arc-electrodes, is a high frequency oscillation circuit and, when connected as shown with a suitable source G, through suitable resistances or impedances R R, said circuit becomes a source of practically continuous electrical oscillations. The frequency of the oscillations developed by said circuit may be increased and the regularity and efficiency of operation of 60 said circuit may be improved if atmospheres of suitable gases other than air be maintained about the arc which is created between the arc-electrodes. By means of the present invention convenient and very efficient means are provided for creating the desired atmosphere and maintaining the same about said arc. 70

In Fig. 1, the electrodes 1, 1, both of which may be of carbon, are supported with 75 in the air-tight vessel 2, one of said electrodes being insulated therefrom, and the lower part of said vessel is filled with a liquid 3 such as water, alcohol-naphtha, benzine, kerosene, etc. The carbon-electrode 80 being porous, operates as a wick to draw the liquid up into the arc where the heat of the latter vaporizes the same. In case the liquid be inflammable, a flame will be maintained about the arc. 85

In Fig. 2, the electrodes 4 may consist of carbon or other suitable substance impregnated with some suitable inflammable material, such as stearin or other hydro-carbon containing element, capable of producing a flame when an arc is maintained in the space between the electrodes.

In the form shown in Fig. 3, 5 represents a jacket of metal or other suitable material incasing the carbon-electrode 1 and a surrounding shell 6 of paraffin, wax, stearin, tallow, etc. In this case the carbon acts as a wick to draw the inflammable substance up into the arc.

In the form shown in Fig. 4, the carbon-electrode 7 is provided with a central core 8 of suitable inflammable material as described above. The receptacle 2 which in closes the electrodes and associated inflammable material, which as aforesaid may be a hydro-carbon, preferably is an air-tight

vessel within which the oxygen is rapidly consumed so as to prevent the combustion within said vessel from too rapidly consuming the fuel or inflammable material. This 5 vessel may be evacuated if desired.

By means of the present invention I am enabled to produce a practically continuous train of high frequency oscillations without having recourse to auxiliary generators of 10 hydrogen or hydro-carbon gas or gases, the whole device being very simple and self-contained.

It will be understood that I do not limit myself to the particular arrangement of 15 electrodes hereinbefore specifically described or to the particular type of circuit shown in the drawings, inasmuch as many modifications may be made in the construction and arrangement of said electrodes and 20 in the oscillation circuits in which they are employed without departing from the principle of my invention.

I claim:

1. In an oscillatory generation system, a 25 circuit, a condenser arranged therein, and means for producing an electric arc also arranged in said circuit, said means including a carbon electrode, having therein a hydro-carbon constituent whereby the consumption 30 of said carbon electrode operates to supply

and maintain an atmosphere containing hydrogen about said arc.

2. In an oscillatory generation system, a 35 circuit, a condenser arranged in said circuit, and means also arranged in said circuit for producing an electric arc, said means containing a carbon electrode having a solid body forming a core of inflammable material.

3. In an oscillatory generation system, a 40 high-frequency oscillation circuit, a carbon arc electrode arranged in said circuit and having a solid body forming a core of hydro-carbon material.

4. In an oscillatory generation system, an 45 oscillation circuit, an arc electrode arranged in said circuit, and consisting of carbon, having a hydrocarbon constituent whereby the consumption of carbon operates to supply 50 and maintain an atmosphere containing hydrogen about the arc, and an air tight casing completely inclosing said electrode.

In testimony whereof, I have hereunto subscribed my name this 3d day of July, 1907.

LEE DE FOREST.
